HOLY-WATER BOTTLE

Alfred F. Reilly, Sr., Taunton, Mass., assignor to Evans
Case Co., North Attleboro, Mass.

Application November 12, 1953, Serial No. 27,561

Term of patent 14 years

(Cl. D58—8)

Fig. 1.

Fig. 2.

Fig. 3.

Fig. 4.

To all whom it may concern:

Be it known that I, Alfred F. Reilly, Sr., a citizen of the United States, residing in Taunton, in the county of Bristol and State of Massachusetts, have invented a new, original, and ornamental Design for a Holy-Water Bottle, of which the following is a specification, reference being had to the accompanying drawing, forming part thereof.

I claim:

The ornamental design for a holy-water bottle, as shown.
